UNITED STATES PATENT OFFICE.

ELEAZER KEMPSHALL, OF NEWTON, MASSACHUSETTS.

DESIGN FOR A BUTTON-ROD.

SPECIFICATION forming part of Design No. 25,698, dated June 30, 1896.

Application filed May 1, 1896. Serial No. 589,909. Term of patent 14 years.

To all whom it may concern:

Be it known that I, ELEAZER KEMPSHALL, of Newton, in the county of Middlesex and State of Massachusetts, have invented and 5 produced a new and original Design for Button-Rods, of which the following is a specification.

This invention relates to a new and original design for a button-rod; and it consists 10 in the novel features of shape and configuration hereinafter fully described and particularly claimed, and clearly illustrated in the drawing.

The drawing is a front elevation showing 15 my design.

The essential feature of my design consists in a rod having a plurality of disks formed with extensions having peripheral grooves or depressions.

a represents a rod. *b* represents disks. *b'* represents extensions of the disks *b*, each of said extensions being formed with a peripheral groove or depression *b²*.

I claim—

The design for a button-rod, or similar articles, substantially as herein shown and described.

In testimony whereof I have signed my name to this specification, in the presence of two subscribing witnesses, this 28th day of April, A. D. 1896.

ELEAZER KEMPSHALL.

Witnesses:

A. D. HARRISON,
P. W. PEZZETTI.
